UNITED STATES PATENT OFFICE.

CHARLES L. HEIZMANN, OF WYOMISSING, PENNSYLVANIA.

DESIGN FOR A PORCELAIN DOOR-KNOB.

51,333.

Specification for Design.

Patented Oct. 9, 1917.

Application filed April 20, 1917. Serial No. 163,531. Term of patent 14 years.

To all whom it may concern:

Be it known that I, CHARLES L. HEIZMANN, a citizen of the United States, residing at Wyomissing, in the county of Berks and State of Pennsylvania, have invented a new, original, and ornamental Design for a Porcelain Door-Knob, of which the following is a specification, reference being made to the accompanying drawing, forming part thereof.

Figure 1 is a plan view of a porcelain door-knob, showing my new design, and Fig. 2 is a side view of the same.

I claim:

The ornamental design for a porcelain door-knob, as shown.

In testimony whereof I affix my signature.

CHARLES L. HEIZMANN.
